US0D1043263S

(12) **United States Design Patent** (10) **Patent No.:** **US D1,043,263 S**
(45) **Date of Patent:** **** Sep. 24, 2024**

(54) **CONTAINER**

(71) Applicant: **LIFETIME PRODUCTS, INC.,**
Clearfield, UT (US)

(72) Inventor: **Robert A. Astle**, Kaysville, UT (US)

(73) Assignee: **LIFETIME PRODUCTS, INC.,**
Clearfield, UT (US)

(**) Term: **15 Years**

(21) Appl. No.: **29/800,630**

(22) Filed: **Jul. 22, 2021**

(51) LOC (14) Cl. **07-10**

(52) U.S. Cl.

USPC **D7/605; D7/313**

(58) **Field of Classification Search**

(57) **CLAIM**

The ornamental design for a container, as shown and described.

DESCRIPTION

FIG. 1 is a top perspective view of a container; FIG. 2 is a bottom perspective view of the container shown in FIG. 1; FIG. 3 is a front view of the container shown in FIG. 1; FIG. 4 is a rear view of the container shown in FIG. 1; FIG. 5 is a left-side view of the container shown in FIG. 1; FIG. 6 is a right-side view of the container shown in FIG. 1; FIG. 7 is a top view of the container shown in FIG. 1; and, FIG. 8 is a bottom view of the container shown in FIG. 1. The broken lines show portions of the container and form no part of the claimed design.

1 Claim, 8 Drawing Sheets
